POWER SYSTEM

Denver W. Miller, Modoc Point, Oreg.

Application February 21, 1939, Serial No. 257,750

2 Claims.

(Cl. 60—1)

My invention relates to power systems, and has among its objects and advantages the provision of an improved steam generator.

In the accompanying drawing:

Figure 1 is a diagrammatic sectional view of a power system in accordance with my invention; and

Figure 2 is a sectional view along the line 2—2 of Figure 1.

In the embodiment selected to illustrate my invention, I make use of a boiler unit 10, heat exchangers 12 and 14 and a condenser unit 16. Boiler unit 10 comprises an inner shell 18 and an outer shell 20 spaced therefrom to provide a space 22 which extends completely about the shell 18. Air from the space 22 may be evacuated for insulation purposes.

Heat exchanger 12 includes an inner shell 24 and an outer shell 26 spaced therefrom to provide a space 28 extending about the shell 24. Shell 26 is connected with the shell 28 in such manner as to provide a communicating port 30. Air is also evacuated from the space 28 in the same manner as the space 22. Similarly, exchanger 14 includes an inner shell 32 and an outer shell 34 spaced therefrom to provide a space 36 which is also evacuated of air. Shell 34 is connected with the shell 26, and I provide a communicating port 38 between the shells. Condenser 16 includes an inner shell 40 and an outer shell 42 spaced therefrom to provide a space 44 from which the air is evacuated. Inner shell 32 of the exchanger 14 communicates with a conduit 46 which extends into the inner shell 40 and is connected with a coil 48, the upper end of which includes a downwardly extending tube 50 terminating short of the bottom of the shell 40.

Shell 20 is provided with a cap 52, while the shell 34 is provided with a similar cap 54. Shell 42 is also provided with caps 56 and 58. In evacuating air from the spaces 22, 28 and 36, these spaces may first be filled with a fluid, which fluid may be poured in through removal of the cap 52. Cap 54 may then be removed, with the cap 52 replaced, and a pump connected with the mount for the cap 54 for pumping the fluid from the system. In filling the system with liquid, all the air is evacuated so that a good vacuum is secured when the liquid is pumped out. Caps 56 and 58 associated with the shell 42 permit the condenser unit 16 to have the air in the space 44 evacuated in the same manner.

Inside the shell 18 I mount a steam engine 60 which may be mounted on suitable supports 62. The engine is provided with a steam inlet pipe 64

having its upper end extending into a steam dome 66. The exhaust pipe 68 of the engine is connected with a header 70 which is connected with an outlet header 72 through the medium of a large number of pipes 74 through which exhaust steam passes.

Inside the shell 18 I mount a heater 76 which may be of the electric type, in which event the heating elements 78 may be enclosed in a suitable housing 80 and connected with wiring extending exteriorly of the casings 18 and 20 through a suitable conduit 82. Heater 76 is mounted on brackets 84, and the heater is submerged in the boiler unit, the level of which water lies beneath the engine 60, as indicated by the line 130 which illustrates the water level in the boiler.

In employing a heater of the electric type, the heater permits the boiler unit to be completely surrounded by an insulating wall structure. Such a system is devoid of frequent direct communication with the atmosphere, as is true of boilers employing fire boxes for steam generating purposes. In the instant case the engine and the heater are completely enclosed inside the boiler and are shielded from the atmosphere, with the heating unit lying in the water in the boiler and the engine located above the water level in the boiler. Such a closed system generates steam in an efficient manner. In locating the engine in the steam space inside the boiler, the engine is heated so that the exhaust steam delivered to the pipes 74 and the headers 70 and 72 will be of relatively high temperature. Water is fed back to the boiler at its bottom and about the headers and pipes so that the exhaust steam is circulated through the headers and pipes surrounded by incoming water.

Outlet header 72 communicates with the shell 24 through the medium of a conduit 86, and the shell 18 has communication with a header 88 inside the shell 24 through the medium of a conduit 90. Shell 24 includes a second header 92 having communication with the header 88 through the medium of a large number of tubes 94. Communication is established between the inner shell 24 and the inner shell 32 through the medium of a conduit 96, and the header 92 is in communication with a header 98 in the shell 32 through the medium of a conduit 100. Header 98 is in communication with a second header 102 in the shell 32 by reason of a plurality of tubes 104.

Pipe 46 communicates with the inner shell 32, while the header 102 is provided with a pipe 106 which extends into the inner shell 40 in the

condenser 16 and is provided with a downwardly extending reach 108. Inside the coil 48 I position a cooling coil 110 connected with pipes 112 and 114 to control the circulation of a cooling fluid through the coil. Inlet pipe 112 may 5 be provided with a valve 116.

The piston rod 118 and the valve rod 120 extend through stuffing boxes 122. In the pipe 106 I interpose a power operated pump 124, which may be operated through any suitable source of power (not shown).

Exhaust steam from the engine 60 is delivered to the header 70 and flows through the pipes 74 and into the header 72 to be delivered to the shell 24 through the medium of the conduit 86. Any condensate forming in the shell 24 flows into the shell 32, and the remaining steam is further condensed as it moves to and into the shell 32. Condensate from the shell 32 flows through the coil 48 and any remaining steam reaching the coil is changed to condensate. Pump 124 operates to remove the water from the shell 40 of the condenser 16 and deliver it to the header 102 for circulation through the tubes 104 and the header 98. From the header 98 the water is delivered to the header 92 for circulation through the tubes 94 and the header 88, after which the water is delivered to the shell 18 of the boiler unit 10. Thus the water in its passage from the condenser unit 16 to the boiler unit 10 is employed as an aid in condensing steam. Similarly, the water as it nears the boiler unit is additionally heated. All the units are effectively insulated because of the vacuum spaces surrounding the units so that the parts are effectively insulated from atmospheric conditions.

Without further elaboration, the foregoing will so fully illustrate my invention that others may, by applying current knowledge, readily adapt the same for use under various conditions of service.

I claim:

1. In a power system, a boiler unit having an

engine located in the steam space of the boiler, a heat exchanger in said boiler near its bottom normally submerged in the water in the boiler, electric heating means for the water located above said heat exchanger and normally submerged in the water in the boiler, a plurality of heat exchangers operatively connected with said first heat exchanger, a condenser connected with one of said plurality of heat exchangers, means 10 for directing exhaust steam from the engine into said first heat exchanger for subsequent passage through all the heat exchangers, and means for moving condensate from the condenser back to the boiler in heat transfer relation with steam and condensate moving through the heat exchangers, with the condensate returned to the boiler entering therein at its bottom and adjacent said first heat exchanger.

2. In a power system, a boiler unit having an 20 engine located in the steam space of the boiler, a heat exchanger in said boiler near its bottom normally submerged in the water in the boiler, electric heating means for the water located above said heat exchanger and normally submerged in the water in the boiler, a plurality of heat exchangers operatively connected with said first heat exchanger, a condenser connected with one of said plurality of heat exchangers, means 25 for directing exhaust steam from the engine into said first heat exchanger for subsequent passage through all the heat exchangers, and means for moving condensate from the condenser back to the boiler in heat transfer relation with steam and condensate moving through the heat exchangers, with the condensate returned to the boiler entering therein at its bottom and adjacent said first heat exchanger.

3. In a power system, a boiler unit having an 30 engine located in the steam space of the boiler, a heat exchanger in said boiler near its bottom normally submerged in the water in the boiler, a plurality of heat exchangers operatively connected with said first heat exchanger, a condenser connected with one of said plurality of heat exchangers, means for directing exhaust steam from the engine into 35 said first heat exchanger for subsequent passage through all the heat exchangers, and means for moving condensate from the condenser back to the boiler in heat transfer relation with steam and condensate moving through the heat exchangers, with the condensate returned to the boiler entering therein at its bottom and adjacent said first heat exchanger, said boiler unit and said plurality of heat exchangers being surrounded by a communicating vacuum space and 40 said condenser being surrounded by a vacuum space.

DENVER W. MILLER.
